Benjamin Rothblum
ATTORNEY

UNITED STATES PATENT OFFICE

BENJAMIN ROTHBLUM, OF NEW YORK, N. Y.

GARMENT

Application filed November 18, 1931. Serial No. 575,792.

This invention relates to garments, and particularly to such as may be used as bathing suits. The principal object is to provide such garment with means whereby it may be readily, rapidly, and conveniently converted to either expose substantially the entire back of the wearer to the invigorating and health imparting action of the sun's rays or to maintain the back of the wearer covered up for comfort, warmth, and protection.

Other objects and advantages will hereinafter appear.

In the accompanying drawing,—

Fig. 1 is a general perspective view of the garment of this invention, showing the back thereof as it appears when in operative state or when covering up the body.

Fig. 2 is a similar view, but showing the back portion of the garment as it appears when in inoperative state or when exposing the back of the wearer.

The garment 1, made of any suitable material, comprises a waist portion 2 forming part of a usual body-portion 3, a chest portion 4, and a back portion 5. Said chest portion is configurated to form a pair of shoulder portions 6 terminating in strap-like portions 7. The back portion 5 may be disposed to either hang downwardly, as shown in Fig. 2, so as to expose the back of the wearer, or it may be disposed in elevated location as shown in Fig. 1 for covering up the back of the wearer. The upper terminal of the back portion 5 is provided with a button 8 or any other suitable fastening device, the terminal of each strap-portion 7 is provided with a button-hole 9 or any other suitable fastening means, and each of the strap-portions 7 is provided with a button 10 set at a proper distance remote from the button-hole 9.

When it is desired to wear the garment with its back portion 5 in operative condition for covering up the wearer's back, the portions 6, 7 may be strung over the wearer's

shoulders in the manner shown in Fig. 1, and the back portion 5 may be then secured thereto by fastening its button 8 to the registering button holes 9 of the two strap portions 7, thereby efficiently supporting the back portion of the garment as indicated. Should it be desired to convert the garment to expose the wearer's back to the sun's rays, the back portion 5 may be unbuttoned from the strap-portions 7 and permitted to drop completely downwardly to the position shown in Fig. 2, and then the strap portions may be secured to each other, to continue their joint support of the chest-portion 4, by fastening the button 10 of each to a button-hole 10a of the other, set remote from said button, and positioning the strap about the rear of the wearer's neck, in the manner illustrated in Fig. 2.

Variations may be resorted to within the scope of the invention.

Having thus described my invention, I claim:

1. A ladies' garment for solar action including a chest portion and a waist portion, a back portion hinged to the rear of said waist portion being swingable about said waist portion to interchangeably cover up or expose the wearer's back, shoulder support portions for said chest portion, said back portion having means for attaching it to and detaching it from said shoulder support portions, and said shoulder support portions having means for securing them to each other upon detachment of said back portion.

2. A ladies' garment for solar action including a chest portion and a waist portion, a back portion hinged to the rear of said waist portion being swingable about said waist portion to interchangeably cover up or expose the wearer's back, shoulder support portions for said chest portion, and each of said shoulder support portions having means at its end for attaching thereto and detaching therefrom said back portion.

3. A ladies' garment for solar action including a chest portion and a waist portion, a back portion hinged to the rear of said waist portion being swingable about said waist portion to interchangeably cover up or expose the wearer's back, shoulder support portions for said chest portion, each of said shoulder support portions having means for attaching thereto and detaching therefrom said back portion, and each of said shoulder support portions having means for attaching them to each other upon detachment of said back portion.

Signed at New York, in the county of New York, and State of New York, this 18th day of November, A. D. 1931.

BENJAMIN ROTHBLUM.
